Primary Examiner—Ruth McInroy*Attorney, Agent, or Firm*—Terry M. Gernstein**[57]****CLAIM**

The ornamental design for a liquid dispenser for a washing machine, as shown and described.

DESCRIPTION

FIG. 1 is a perspective view of a liquid dispenser for a washing machine showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof; and,
FIG. 7 is a bottom plan view thereof.
The bubbles shown in broken lines in FIGS. 1, 2, 4 and 5 are shown for illustrative purposes only and form no part of the claimed design.

FIG. 1.

FIG. 4.

FIG. 2.

FIG. 3.

FIG. 5.

FIG. 7.

FIG. 6.
